(57) **CLAIM**

The ornamental design for a hands-free umbrella harness, as shown and described.

DESCRIPTION

FIG. 1 is a front view of a hands-free umbrella harness showing my new design;

FIG. 2 is a back view thereof;

FIG. 3 is a side view thereof;

FIG. 4 is an opposite side view thereof;

FIG. 5 is a top view thereof; and,

FIG. 6 is a bottom view thereof.

In FIGS. 2, 3, 4 and 6, the broken lines showing of environmental structure for purposes of illustrating the hands-free umbrella harness in a condition of use. The broken lines and the structure they depict form no part of the claimed design.

1 Claim, 6 Drawing Sheets

FIG. 1

FIG. 2

FIG. 3

FIG. 4

FIG. 5

FIG. 6
